WASHING MACHINE

Philetus A. Grove, Sr., Detroit, Mich.

Application March 12, 1936, Serial No. 68,490

4 Claims. (Cl. 259—77)

The present invention relates to new and useful improvements in washing machines particularly for domestic use and has for its primary object to provide, in a manner as hereinafter set forth, 5 a device of this character embodying a novel construction and arrangement of rotary tub and agitator, together with common means for manually actuating said tub and agitator simultaneously in opposite directions.

10 Other objects of the invention are to provide a washing machine of the aforementioned character which will be comparatively simple in construction, strong, durable, highly efficient and reliable in use, compact, light in weight and which 15 may be manufactured at low cost.

All of the foregoing and still further objects and advantages of the invention will become apparent from a study of the following specification, taken 20 in connection with the accompanying drawings wherein like characters of reference designate corresponding parts throughout the several views, and wherein:—

Figure 1 is a view in front elevation of a washing machine constructed in accordance with the 25 present invention.

Figure 2 is a top plan view of the invention with the cover omitted.

Figure 3 is a vertical sectional view, taken substantially on the line 3—3 of Figure 1.

30 Figure 4 is a view in bottom plan of the tub and turntable.

Figure 5 is a top plan view of the invention with the tub and other portions omitted, the operating lever and agitator shaft being shown in 35 horizontal section, certain portions being broken away to expose the drive mechanism.

Figure 6 is a view in horizontal section, taken substantially on the line 6—6 of Figure 3.

Figure 7 is a detail view in vertical section, 40 taken substantially on the line 7—7 of Fig. 3.

Figure 8 is a detail view in perspective of the lever which actuates the tub and the agitator.

Referring now to the drawings in detail, it 45 will be seen that the embodiment of the invention which has been illustrated comprises a supporting stand which is designated generally by the reference numeral 1. Mounted on the supporting stand 1 below the top thereof is a base or platform 2 on which the hub 3 of a turntable 4 is mounted for rotation, said hub 3 being mounted on a thrust bearing 5. The turntable 4 includes a depending peripheral flange 6. Rollers 7 are provided on the supporting stand 1 for the turntable 4.

50 Secured on the turntable 4 is a tub 8 which is

open at its top, said tub being provided with a suitable removable cover 9. The tub 8 further includes a corrugated lining 10.

Rising from the bottom of the tub 8 is a centrally located stand tube 11 having a suitable bearing 12 in its closed upper end in which the upper end portion of a vertical shaft 13 is journaled. Secured on the upper end portion of the shaft 13 and depending therefrom for rotation about the stand tube 11 is an agitator 14. The 10 shaft 13 extends downwardly through the hub 3 and the platform 2 and has fixed on its lower end portion a sprocket gear 15.

Pivotedly mounted at an intermediate point, 15 as at 16, below the platform 2 for swinging movement in a horizontal plane is a lever 17 having a fork 18 on one end. Extending between the arms of the fork 18 is a sprocket chain 19 (see Figure 5) which is engaged with the gear 15. The lever 17 further includes an upturned outer 20 portion 20 which terminates in an inturned arm 21 which is engaged in a stirrup or the like 22 which depends from the tub 8.

Mounted on the lower portion of the supporting stand 1 is a bracket 23 to which one end of a 25 hand lever 24 is pivotally connected, as at 25. At an intermediate point the hand lever 24 is loosely connected to the portion 20 of the lever 17 by a pin and slot connection 26. A guard 27 is provided on the upper portion of the supporting stand 1 for the levers 17 and 24. The reference numeral 28 designates a drain for the tub 8.

It is thought that the operation of the invention will be readily apparent from a consideration of the foregoing. When the hand lever 24 is 35 swung in one direction the tub 8 is actuated in a corresponding direction by reason of the engagement of the arm 21 of the lever 17 in the stirrup or the like 22. However, the inner end of the lever 17, which carries the chain 19, will be 40 swung in the opposite direction in a manner to rotate the agitator 14 in the opposite direction to that in which the tub 8 is moving. It will thus be seen that the tub 8 and the agitator 14 may be rapidly oscillated in opposite directions through 45 the medium of the hand lever 24.

It is believed that the many advantages of a washing machine constructed in accordance with the present invention will be readily understood, and although a preferred embodiment of the device is as illustrated and described, it is to be understood that changes in the details of construction, and in the combination and arrangement of parts may be resorted to which will fall within the scope of the invention as claimed. 50 55

What is claimed is:—

1. A washing machine comprising a supporting stand, a tub rotatably mounted on said supporting stand, an agitator rotatably mounted in said tub, a lever pivotally mounted, at an intermediate point, on the supporting stand, means underlying the tub operatively connecting the tub to one end of said lever for actuation thereby in one direction, means underlying the tub operatively connecting the agitator to the other end of the lever for actuation thereby in the opposite direction, and means for actuating said lever.

2. A washing machine comprising a supporting stand, a tub rotatably mounted on said supporting stand, an agitator rotatably mounted in said tub, a lever pivotally mounted, at an intermediate point, on the supporting stand, an arm on one end of the lever and underlying the tub operatively connected to the tub for rotating said tub in one direction, means underlying the tub operatively connecting the other end of the lever to the agitator for rotating said agitator in the opposite direction, and a hand lever pivotally mounted on the supporting stand and operatively connected to the first-named lever for actuating the same.

3. A washing machine comprising a supporting stand, a tub rotatably mounted on said supporting stand, a vertical rotary shaft extending into the tub from the bottom thereof, an agitator

mounted on said shaft for rotation therewith in the tub, a sprocket gear on the lower end portion of said shaft, a lever pivotally mounted, at an intermediate point, on the supporting stand, a fork on one end of said lever, a sprocket chain mounted on said fork and engaged with the sprocket gear for actuating the agitator in one direction, means connecting the other end of the lever to the under side of the tub for actuating said tub in the opposite direction, and means for actuating said lever.

4. A washing machine of the class described comprising a supporting stand, a platform on said supporting stand, rollers mounted on the supporting stand, a turntable mounted on the rollers, said turntable including a hub journaled on the platform, a tub fixed on the turntable, a rotary shaft extending vertically through the platform, the hub, the turntable and the bottom of the tub, an agitator fixed on the upper end portion of said shaft for rotation in the tub, a lever pivotally mounted, at an intermediate point, on the supporting stand, means operatively connecting the shaft to one end of the lever for actuation in one direction thereby, means operatively connecting the tub to the other end of said lever for actuation in the opposite direction thereby, and a hand lever operatively connected to the first named lever for actuating the same.

PHILETUS A. GROVE, Sr. 30
